UNITED STATES PATENT OFFICE.

MAURICE DENIS, OF PARIS, FRANCE.

MACHINE FOR SPINNING, WASHING, AND DRYING VISCOSE THREADS.

1,408,350.

Specification of Letters Patent. Patented Feb. 28, 1922.

Application filed March 31, 1921. Serial No. 457,469.

(GRANTED UNDER THE PROVISIONS OF THE ACT OF MARCH 3, 1921, 41 STAT. L. 1313.)

To all whom it may concern:

Be it known that I, MAURICE DENIS, a citizen of the French Republic, and a resident of 95 Rue de Prony, Paris, France, have invented new and useful Improvements in a Machine for Spinning, Washing, and Drying Viscose Threads, (for which I have filed applications in Belgium Aug. 8, 1913; France Mar. 24, 1919; Italy Apr. 1, 1919; 10 Great Britain Apr. 8, 1919; Germany July 17, 1920,) of which the following is a specification.

This invention relates to the manufacture of artificial silk by the viscose process, and 15 has for its object to provide an improved machine for simultaneously spinning, washing and drying the viscose thread in a continuous manner; this machine is of the kind in which the viscose thread, on issuing from 20 each of the squirming nozzles, plunges directly, within a container, having the shape of a test-tube, and surrounding the nozzle, into a coagulation bath travelling, along a closed circuit, in the same direction as the 25 viscose thread.

According to the present invention, the test tube containing the coagulation bath is adjustable vertically with respect to the squirming nozzle, so as to allow of regulating 30 the length of travel of the viscose thread in the coagulation bath, which is an important condition in order to obtain a good coagulation of the thread.

Said arrangement also allows the workers 35 to collect easily the filaments issuing from the squirming nozzles at the beginning of the manufacture, or to clean, open or replace easily and readily a squirming nozzle, if required.

40 The accompanying drawings illustrate by way of example one practical form of this invention.

In these drawings:

Fig. 1 is a vertical cross section of the improved machine constructed according to this invention.

Fig. 2 is a partial front elevation.

Figs. 3 and 4 are horizontal sections taken on the lines 3-3 and 4-4 respectively of 50 Fig. 2.

1 is a feeding conduit for bringing the viscose solution in the requisite conditions of pressure, temperature and concentration

to each of the squirming nozzles. Between this conduit and the several squirming 55 nozzles proper, there is interposed a double filtering apparatus for the solution in such a manner as to arrest any impurities that may be present before they reach the squirming nozzles which otherwise they would 60 choke, to the detriment of the quality of the resulting product.

Each filtering apparatus comprises two groups A and B designed to enable the corresponding squirming nozzle to have a continuous 65 operation, one of the two groups feeding the squirming nozzle whilst the other group is being stopped for replacing the soiled filter which it comprises.

Each of the two filtering groups A and B 70 consists of a filtering box 3, connected to the feeding conduit 1 by a union with a cock 2, and communicating on the other hand with the corresponding nozzle by means of a union with a cock 4 (Fig. 2). 75

Each filtering box 3 comprises a cylindrical reservoir, closed at its upper end by a screw-threaded plug 29 and provided at its lower end with a screw-threaded ring 30 which keeps the filtering disc in place. In 80 the plug 29 there works a pointed screw 31 which allows, on replacing the filter into operation before the cock 4 is opened (the cock 2 being open), of discharging any air that may have entered the cylindrical reservoir 85 during the changing of the filter.

The two unions with cocks 4, coming from the two filter boxes 3 corresponding to each nozzle, are fitted with ebonite unions 5 connected, by means of rubber sleeves 7, to a 90 glass V-tube 6 which is likewise provided with a union 8, connected by means of a rubber sleeve 10 (mounted on an adjustable support and keeping the whole in place, Fig. 1) with the union 9 of a glass tube 11 of suitable length, on the screw-threaded ebonite sleeve 13 that carries the squirming nozzle 14 (Fig. 1).

On leaving the nozzle 14, the viscose thread plunges directly into a coagulating 100 bath contained in a glass container 15, having the shape of a test tube of suitable length, and provided at 16 with an overflow, which connects at 17 with a flexible rubber pipe 22 that is connected in turn to a collector 23. 105

An up-take casing 25, provided with a movable part, 26, constitutes the foot of the apparatus.

A pipe 18 serves for feeding the coagulating bath contained in the several containers 15 corresponding to all the nozzles; this pipe 18 is connected (Figs. 2 and 3), by means of nozzles 19, with cocks 20, and by means of a bent tube 21' for each nozzle, to a pipe 21 that dips into the corresponding container 15. By this means each pipe 21 can be adjusted in the desired position in the corresponding test-container 15.

Above and behind the nozzles 14 are arranged two cylinders or rollers 39, preferably of aluminium, by which there is driven at a suitable speed an endless fine metallic web 40 preferably of aluminium, on which are fixed at intervals small hooks 38 for receiving the filaments 37 issuing from the nozzles 14.

41 is a pipe provided with a cock for supplying the nozzles 42 which are designed to project a suitable liquid upon the endless web 40. The liquid thus projected after it has passed through the endless web 40, is collected in a series of troughs 43 for subsequent regeneration and re-use.

A second series of nozzles 44, fed by a pipe 44', serves to project another liquid against the endless web 40. Inside the latter, and near its lower end is a further nozzle 45 which directs a jet in the direction opposite to the foregoing ones on to the endless web 40.

A second endless metallic web 48, similar to the preceding, travels over rollers 47-47 that are rotated at a suitable speed. Between the two stretches of the endless web 48 there is interposed a casing of sheet metal 49, the rear wall 50 of which is perforated so as to allow of the passage therethrough, in the direction of the arrows (Fig. 1), of hot air that is supplied by a pipe 51 and is drawn by a fan connected to the pipe 52. Above this endless web 48 is a disc 55 carrying the spindle of a bobbin with a thread-guide. This disc is driven by friction from a roller 56.

50 The liquids, projected on to the endless web 40 by the nozzles 44 and 45, are collected by a sheet metal casing 61 which encloses the endless webs 48 and 40.

The framing and the various parts supporting the rollers, cylinders, nozzles, etc., are not shown in the drawings for the sake of clearness of the latter.

The operation of the improved apparatus is as follows:

60 The liquid constituting the coagulating bath is brought in the required conditions of temperature, concentration and volume, from the general supply conduit 18 into the lower part of each container 15. It fills this container until the level of the overflow 16

is reached, and it then overflows through the pipes 17 and 22 into the collector 23, whence it is returned, after having been purified, regenerated and reheated, to the feed conduit 18. The flow of the coagulating liquid is regulated by the cock 20, according to the velocity of the issuing filament.

The coagulating bath, in flowing through the coagulating container 15 in the direction of the travel of the viscose thread, thus makes a closed circuit in the course of which it becomes purified, regenerated and made ready for re-use according to the desired temperature.

The solution of viscose, supplied by the pipe 1 in the requisite conditions of concentration, temperature and pressure, is purified in the filter box 3 of the filtering group A or B (according as one or the other of these groups is in operation) and passes through the union 6, the pipe 11-12, and the nozzle 13 carrying the squirming nozzle 14, and squirts into the coagulating bath contained in the container 15.

When it is required to open, clean or replace a squirming nozzle 14, or to collect the filaments at the commencement of the manufacture, the container 15 is lowered so as to leave above the upper level of the nozzle 14 only the minimum height necessary for the coagulation of the filament, and allow the hand labour of the workmen, charged with collecting the first thread, to be performed under the best conditions.

For this purpose the glass container 15 is carried (Fig. 2) by two aluminium collars 35, 36, sliding along guide pillars 31 of aluminium of glass supported by collars or sleeves 33 on the conduit 18. The devices provided for supplying and discharging the coagulating liquid are such that this container 15 can be lowered (into the position indicated in dotted lines in Fig. 2) without the liquid contained therein overflowing therefrom. It can also be kept in a determined position for regulating the length of filament submerged according to the velocity of travel of said filament and therefore regulating the length of the sojourn of the jet of viscose which is squirted into this medium.

As soon as the thread 37 issuing from the squirming nozzles 14 has been delivered to the drawing devices 38, the container 15 is brought into a position satisfying the conditions for the sojourn of the thread in the medium of the coagulating bath.

The resulting injurious vapours are sucked through a perforated plate 27 by a pipe 28 connected to any suitable suction apparatus.

125 The thread 37, produced by the union of the filaments issuing from the several orifices of a squirming nozzle 14, is attached in passing to one of the hooks 38 carried by the endless metal web 40, and is drawn

along by the latter at a determined speed. The lengths of the metal webs 40 and 48 are determined according to the requirements ascertained by experiment in relation to the 5 coagulation and the complete washing and drying of the viscose thread.

If the first coagulating bath contained in the container 15 has had an insufficient effect upon the viscose thread, the nozzles 42 10 may spray the thread, as it travels along with the endless web 40 for a determined length and number, with a liquid suitable for completing the coagulation. This liquid will in part be collected by the trough 15 device 43 for the purpose of subsequent regeneration.

The nozzles 44 will likewise suitably wash the coagulated thread under suitable conditions of space and duration. The jet of 20 the inner nozzles 45 will unstick the thread from the metal web 40 and will facilitate the transference from this web 40 on to the endless web 48 upon which it will be dried by the action of a current of hot air supplied 25 through the pipe 51 in the casing 49. The thread is then wound on the bobbin 55.

Having now particularly described and ascertained the nature of my said invention, and in what manner the same is to be performed, I declare that what I claim is:

1. A machine for spinning, washing and drying viscose thread in a continuous manner, comprising squiring nozzles, means for feeding said squiring nozzles with the viscose solution, a glass container surrounding each of said squiring nozzles and containing the coagulation bath through which pass the filaments of the thread issuing from the squiring nozzle, means for drawing 35 along the viscose thread at a predetermined speed, means for circulating said coagulation bath in the same direction as the viscose thread, together with means for vertically adjusting the position of each glass- 40 container with respect to the corresponding squiring nozzle, for the purpose described.

2. A machine for spinning, washing and drying viscose thread in a continuous manner, comprising squiring nozzles, means for 45 feeding said squiring nozzles with the viscose solution, a glass container surrounding

each of said squiring nozzles and containing the coagulation bath through which pass the filaments of the thread issuing from the squiring nozzle, means for drawing 55 along the viscose thread at a predetermined speed, means for circulating said coagulation bath in the same direction as the viscose thread, means for vertically adjusting the position of each glass container with 60 respect to the corresponding squiring nozzle, for the purpose described, means for attaching the viscose thread, issuing from the coagulation bath, to an endless web, travelling at a predetermined speed, means 65 for spraying said thread with a liquid adapted to complete its coagulation, means for spraying the thread with a washing liquid, means for unsticking said thread from the endless travelling web, means for drying 70 said thread, carried over by another endless web, by a current of hot air, before the said thread is wound on a reel.

3. A machine for spinning, washing and drying viscose thread in a continuous manner, comprising a set of squiring nozzles, a main supply conduit for feeding the viscose solution to said nozzles, and, between said supply conduit and each nozzle, a pair of filtering devices, means for placing one 80 of them temporarily out of operation whilst the continuous filtration of the viscose solution is being carried on by the other one, a glass container surrounding each of said squiring nozzles and containing the coagulation bath through which pass the filaments of the thread issuing from the squiring nozzle, means for drawing along the viscose thread at a predetermined speed, means for circulating said coagulation bath 85 in the same direction as the viscose thread, together with means for vertically adjusting the position of each glass-container with 90 respect to the corresponding squiring nozzle, for the purpose described. 95

In testimony whereof I have signed my name to this specification.

MAURICE DENIS.
